LAST JACK

Elton G. Carr, Beverly, Mass., assignor to United Shoe Machinery Corporation, Borough of Flemington, N. J., a corporation of New Jersey

Application June 14, 1940, Serial No. 340,480

9 Claims. (Cl. 12—123)

This invention relates to a device for supporting a last upon which a partly finished shoe is disposed, and is herein illustrated as embodied in a last jack provided with an improved self-locking last pin.

During the manufacture of shoes, the lasted shoes are frequently mounted on jacks, for example, during the application of a spray coating to a part thereof, or during certain other finishing operations. The customary last jack is provided with a smooth last pin which loosely fits into the thimble hole of the last and, consequently, unless the last pin is maintained in a substantially upstanding position, the last will fall off of the last pin. Accordingly, the last pin of the present invention is provided with a locking element whereby the last may be held on the last pin even when the last pin is inverted, as, for example, when it is desirable to support the last from above.

It is not uncommon to provide last pins with means for locking the last on the last pin. However, heretofore, these last pins have not been entirely satisfactory because the locking elements were not adapted to rapid mounting and dismounting of the last.

It is an object of the present invention, therefore, to provide an improved self-locking last pin upon which a last may be mounted and dismounted with very little manipulation.

To this end, in accordance with the present invention, a last pin is provided for securing a last placed thereon, the last pin being mounted on a support and having two portions of substantially the same cross section, the portions being so constructed and arranged that one of the portions is normally urged to take a laterally offset position with respect to the other portion whereby a last placed upon the last pin will be locked thereon, means being provided, however, for moving the first-named portion into end-to-end alinement with the second-named portion to release the last.

The form and applications of the invention will now be described with reference to the accompanying drawing, in which—

Fig. 1 is an elevation of the last support in section showing a last mounted therein;

Fig. 2 is a plan view of the device;

Figs. 3 and 4 show on a smaller scale the last pin applied to a shoe rack; and

Figs. 5 and 6 show the last pin applied to a shoe conveyor.

Referring to Fig. 1, the device, generally indicated by the letter P, is shown mounted on a

bracket 10 extending from a support 12 in a spray booth, for example, for supporting a last L having a shoe S mounted thereon preparatory to the application of a spray coating thereto, or to some finishing operation. As illustrated, the device comprises a two-part last pin consisting of a portion 14 arranged to extend through an aperture 16 formed in the bracket 10 and a portion 24 forming a longitudinal extension of the portion 14 the two portions being aligned end to end. An enlargement 18 formed near one end of the portion 14 provides an annular shoulder 20 adapted to bear against the top surface of the bracket whereby the portion 14 is fixed to the bracket by any convenient means, as, for example, by brazing or soldering.

The last manufacturers commonly adhere to a standard-sized thimble 22 and, consequently, the portions 14 and 24 of the last pin are turned down to a diameter of approximately $\frac{3}{16}$ " less than the standard thimble, thereby providing a relatively snug fit between the last pin and thimble and yet permitting one readily to mount or dismount the last on the pin.

The portion 24 is constructed and arranged so that it may be moved relatively to the portion 14 about an axis offset from the axis of the portion 14 whereby the last may be locked on the last pin or released therefrom. This is effected by a spindle 26 to one end of which the portion 24 is fixed, the spindle being mounted for rotation in a bore 27 formed longitudinally of the portion 14 and eccentric to its axis. The opposite end of the spindle 26 projects through the enlargement 18, and a collar 28 is fixed thereto by a cotter 25 to retain the spindle in the bore 27. A thumb-piece 29 extends radially from the collar whereby the spindle may be turned to move the portion 24 from locking position into end-to-end alinement with the portion 14.

It is desirable to have a self-locking last pin so that when the operator brings the portions 14 and 24 into concentric relation by means of the thumb-piece 29 and places the last on the last pin, it will only be necessary to release the thumb-piece 29 to lock the last on the last pin. To this end, a torsion spring 30 is placed on the enlargement 18, one end 32 of the spring being anchored in an aperture in the bracket 10 and the other end being extended to form a loop about the thumb-piece at 34. The spring is so arranged that normally it will act upon the spindle to urge the portion 24 laterally into an offset or eccentric position with respect to the fixed portion 14. Therefore, when a last is placed

upon the last pin and the thumb-piece released, the spring automatically forces the movable portion 24 to a laterally offset or eccentric position with respect to the fixed portion, thereby tightly gripping the walls of the last thimble and locking the pin to the last. In order to release the last, the thumb-piece is turned in opposition to the spring to move the movable portion into concentric position with relation to the fixed portion.

While the eccentric relation of the parts of the last pin retains the last on the last pin, if the last is gripped and moved in a direction to decrease the eccentricity of the parts of the last pin, the last may be turned on the last pin. To prevent this relative movement between the last and the last pin, which would be particularly undesirable when the last pin is used on a rack or conveyor, as will appear hereinafter, a depending flange 35 is formed integral with the bracket 10, the lower portion of the flange being adapted to engage the neck of the last. Due to the fact that the neck of the last is oval, the engagement of the flange with the side portion thereof prevents rotation of the last on the last pin.

As thus far described, the last jack is well adapted for supporting a last in a spray booth, but it may be employed for supporting lasts for various other steps of the shoe manufacturing process. For example, after each operation the lasted shoes are placed on racks and temporarily set aside or moved directly to the next operation. The racks are pushed about rapidly and frequently jostled so that some of the shoes fall off. It is within the object of this invention to equip shoe racks with a plurality of last pins of the type described above fixedly to support the lasted shoes on the racks. Referring to Fig. 4, there is illustrated a fragmentary portion of a shoe rack 36 having a number of parallel bars 38 upon which there are mounted a plurality of last pins P. The bars 38 are L-shaped members set at an angle (Fig. 3) so that one face 40 of each alternate bar slopes upwardly from the horizontal when facing either side of the rack. The last pins are fixed to the faces 40 of the bars 38 in the same manner that the last pin P is fixed to the bracket 10 in Fig. 1, and as a result, they extend downwardly to the front on alternate bars, as viewed from either side of the rack. The reason for having the last pins in this position is to permit the operator to mount the lasts on the pins by an upward sweep of the arm, which consumes less time and effort than to raise the lasts above the last pins and to push them down onto the last pins. Furthermore, to release the last it is only necessary to actuate the thumb-piece whereupon the last will drop off into the operator's hand by gravity, thereby eliminating any necessity for pulling and lifting the last from the last pin.

In some factories endless conveyors are used for conveying the shoes from one operation to the next, and Figs. 5 and 6 show the last jack of this invention as applied to such a conveyor. A conventional type of conveyor is illustrated comprising a frame 42 upon which there are mounted endless parallel chains 44 between which there are cross links 48. Each cross link has secured thereto an angle plate 50 to which there is fixed a last pin P (Fig. 6). The endless conveyor may be placed so that the lasts may be carried along by either the upper run of the chain or the lower run. An advantage of the lower run is that the operator can release the

lasts as they pass over his bench by pressing the thumb-piece without having to pull or lift the lasts from the pins.

It is to be understood that the illustrations of the applications of this invention as set forth above are by way of example only and that other applications may be made by those skilled in the art without departing from the invention as defined in the following claims.

Having described my invention, what I claim as new and desire to secure by Letters Patent of the United States is:

1. A last jack comprising, in combination, a support and a last pin, said last pin comprising two portions of substantially the same cross-section alined end to end, means for urging one portion to turn about an offset axis substantially parallel to the axis of the other portion so that a part of said first-named portion is laterally offset with respect to the other portion, and means for moving said first-named portion into endwise alinement with the second-named portion.

2. A last jack comprising, in combination, a support and a last pin, said last pin comprising a fixed portion and a movable portion of substantially the same cross-section, means for urging said movable portion to turn about an offset axis substantially parallel to the axis of the fixed portion so that a part of the movable portion is laterally offset with respect to the fixed portion, and means for moving said movable portion into endwise alinement with the fixed portion.

3. A last jack comprising, in combination, a support and a last pin, said last pin comprising two portions alined end to end, means for urging one of said portions to turn about a longitudinal axis so that a part of its surface is laterally offset with respect to the other of said portions, and means to move said first-named portion into alinement with the second-named portion.

4. A last jack comprising, in combination, a support and a last pin, said last pin comprising two longitudinally alined portions of substantially the same diameter, means for normally urging one portion to turn about a longitudinal axis to a position eccentric to the other portion, and means for moving said first-named portion to a position concentric to the second-named portion.

5. A last jack comprising, in combination, a support and a last pin, said last pin comprising two portions movable relatively to each other, said portions being of substantially the same diameter, a spring normally urging one portion to take a position eccentric to the other portion, and means for moving said first-mentioned portion into a position concentric to said second-named portion.

6. A last jack comprising, in combination, a support and a last pin, said last pin comprising two portions of substantially the same diameter, one of said portions having a longitudinal bore formed therein, a spindle disposed in said bore, the other of said portions being fixed to said spindle, and means urging said spindle to turn in said bore to displace said second-named portion laterally of said first-named portion.

7. A last jack comprising, in combination, a support and a last pin, said last pin comprising a movable portion and a fixed portion, a spring for normally urging said movable portion to take a laterally offset position with respect to the fixed portion, and a thumb-piece operably con-

nected to said movable portion whereby said movable portion may be moved to a position concentric to the fixed portion.

8. A last jack comprising, in combination, a support and a last pin, said last pin comprising two portions, a bore extending through one portion, a spindle disposed in said bore, said spindle being connected to the other portion, a spring normally urging said spindle to turn in said bore to displace the second-named portion laterally of the first-named portion, and a thumb-piece fixed to said spindle whereby said spindle may be turned to a position in which the second-named

portion is concentric to the first-named portion.

9. A last jack comprising, in combination, a support and a last pin mounted thereon for receiving a last, said last pin comprising two portions, means for urging one portion to a laterally offset position with respect to the other portion, means for moving said first-named portion into alignment with the second-named portion, and means associated with said support to engage the neck of the last to prevent rotation thereof relatively to the last pin.
